BOTTLE OR SIMILAR ARTICLE

George J. Utz, Lancaster, Ohio, assignor to Anchor Hocking Glass Corporation, Lancaster, Ohio, a corporation of Delaware

Filed Dec. 30, 1964, Ser. No. 83,237

Term of patent 14 years

(Cl. D58—9)

FIG. 2.

FIG. 1 is a front elevational view of bottle or similar article showing my new design; and

FIG. 2 is a side elevational view thereof.

The dominant features of my design reside in the portions shown in full lines.

I claim:

The ornamental design for a bottle or similar article, substantially as shown and described.
